(57) **CLAIM**

I claim the ornamental design for a dispensing closure, as shown and described.

DESCRIPTION

FIG. 1 is a perspective view of one embodiment of the dispensing closure with the lid closed.

FIG. 2 is a top plan view of the dispensing closure in FIG. 1, the bottom forming no part of the claimed design.

FIG. 3 is a front elevational view of the dispensing closure in FIGS. 1 and 2.

FIG. 4 is a side elevational view of the dispensing closure in FIGS. 1–3, the opposing side elevational view being a mirror image of FIG. 4.

FIG. 5 is a rear elevational view of the dispensing closure in FIGS. 1–4.

FIG. 6 is a perspective view of the dispensing closure of FIGS. 1–5 with the lid open.

FIG. 7 is a perspective view of a second embodiment of the dispensing closure with the lid closed.

FIG. 8 is a top plan view of the dispensing closure in FIG. 7, the bottom forming no part of the claimed design.

FIG. 9 is a front elevational view of the dispensing closure in FIGS. 7 and 8.

FIG. 10 is a side elevational view of the dispensing closure in FIGS. 7–9, the opposing side elevational view being a mirror image of FIG. 10.

FIG. 11 is a rear elevational view of the dispensing closure in FIGS. 7–10; and,

FIG. 12 is a perspective view of the dispensing closure of FIGS. 7–11 with the lid open.
